(57) **CLAIM**

The ornamental design for an inflatable geometric play structure with tunnel, as shown and described.

DESCRIPTION

FIG. 1 is a perspective view of an inflatable geometric play structure with tunnel;

FIG. 2 is a right side view of the of the inflatable geometric play structure with tunnel, the left side view (omitted) being a mirror image thereof;

FIG. 3 is a front view of the inflatable geometric play structure with tunnel, the rear view (omitted) being a mirror image thereof;

FIG. 4 is a bottom view of the inflatable geometric play structure with tunnel;

FIG. 5 is a top view of the inflatable geometric play structure with tunnel; and,

FIG. 6 is a perspective view of the inflatable geometric play structure with tunnel employed in an inflatable play structure system.

The broken line showing of is included for the purpose of illustrating and forms no part of the claimed design.
